UNITED STATES PATENT OFFICE.

JOHN R. BARRE, OF LOS ANGELES, CALIFORNIA, ASSIGNOR TO STANDARD FELT COMPANY, OF WEST ALHAMBRA, CALIFORNIA, A CORPORATION OF CALIFORNIA.

STRETCHING AND DRYING RACK.

1,237,742.

Specification of Letters Patent. Patented Aug. 21, 1917.

Application filed May 13, 1916. Serial No. 97,443.

To all whom it may concern:

Be it known that I, JOHN R. BARRE, a citizen of the United States, residing at Los Angeles, in the county of Los Angeles and 5 State of California, have invented a new and useful Stretching and Drying Rack, of which the following is a specification.

My invention relates to the art of manufacturing felted sheets. The principal object of my invention is to provide novel stretching and drying means by which wet 10 felt sheets may be stretched into a flat condition and quickly dried while in this condition.

15 A further object of my invention is to provide a rack on which these sheets may be stretched and to provide this rack with casters so that the stretching operation may be performed under ordinary conditions of 20 temperature and humidity, the rack then being rolled into a drying chamber which has controllable conditions as to temperature and humidity.

25 A further object of the invention is to provide novel mechanism by which the sheets can be stretched.

In the drawings, which are for illustrative purposes only:

30 Figure 1 is a side view of a preferred form of rack.

Fig. 2 is a sectional plan on a plane represented by the line x^2-x^2 of Fig. 1 of a portion of a rack, this plane being viewed in the direction of the arrows.

35 Fig. 3 is a side view of the jack.

Figs. 4 and 5 are elevations of portions of alternate forms of my invention.

Fig. 6 is a view of the ratchet used in the form shown in Fig. 5.

40 In the form of the invention shown in Fig. 1, a pair of standards 11, preferably formed of pipe, are provided, each of these standards fitting inside of the upper portion 12 of a tee 13, the standards 11 being free 45 to turn freely in the tees 13. Secured on either branch of the tee 13 are pipe members 14, these pipe members having at their extreme ends casters 15. Secured near the top of the standards 11, by means of a nut 16, a washer 17, and a key 18, is an upper stretching member 19. The standards 11 are connected by tees 20, these tees being connected by a cross brace 21.

50 Sliding freely on the standards 11 is a lower stretching member 22. Secured in the

upper stretching member 19 are pipe braces 25, these pipe braces extending down and connecting into a casting 26 in which a threaded stem 27 is rigidly secured. The stem 27 forms a portion of a jack 28, said 60 jack being provided with a nut 29 fitting on the stem 27, this nut being rigidly secured to a bevel gear 30 which is driven through a bevel gear 31 from a handle 32. This form of screw jack is old and no claims to 65 novelty are made thereon. All these parts are supported in proper relationship by a frame 33 which is secured by bolts 34 to the lower stretching member 22.

Secured to the upper stretching member 70 19 are hooks 35, and secured to the lower stretching member 22 are similar hooks 36. The stretching members 19 and 22 are preferably of channel section, and the hooks 35 and 36 are preferably placed on either side 75 thereof to provide space for securing the felt.

The method of operation is as follows:

The jack 28 is actuated to draw the members 19 and 22 close together, and the strip 80 of felt to be dried is secured on the hooks 35 and 36, two sheets of felt being commonly dried at once, one being placed on either side of the stretching members 19 and 22. After the felt has been suitably secured on 85 the hooks 35 and 36, the jack 28 is operated by the handle 32 to move the stretching members 19 and 22 apart, thereby exerting tension on the felt and pulling it flat. The handle 32 is so located that it can be readily 90 manipulated by the operator reaching between the sheets of felt from either side. The pipe members 14 are commonly located at right angles to the members 19 and 22 during the stretching operation, which 95 stretching operation is performed outside of the drying room. The rack, with its wet felt sheets attached, is then wheeled into the drying room on the casters 15, and if desired the members 14 can be turned parallel to the members 19 and 22, so that a 100 large number of racks may be put in the drying room without occupying excessive space.

In the alternate form shown in Fig. 4, the 105 upper member 19 is not shown, the standards 11 being secured to tees 13 in an exactly similar manner to that already described in connection with Fig. 1. The lower stretching member 22 slides freely on the stand- 110

ards 11, tension springs 50 being provided on either side thereof, so that it naturally tends to assume an upper position. A pair of chains 51 are secured in eye bolts 52 in the member 22, these chains passing down and around a shaft 53 which is pivoted in castings 54 secured in the standards 11. A ratchet wheel, 55, which is worked through a pawl 56 and a lever 57, is secured on the end of the shaft 53, a pawl 58 secured in a casting 59 being provided to hold the ratchet wheel 55 in any position. The felt is secured on either side of the members 19 and 22 as previously described, and the chains 51 are wound up on the shaft 53 by means of a lever 57 and a ratchet 56. In the form of the invention illustrated in Fig. 5, the lower stretching member 22 is provided with standards 64 which are pivoted thereto at 65, these standards having a plurality of holes 66 by which they may be secured by means of pins 67 to levers 68 and 69. The levers 68 and 69 are pivoted on pins 70 carried on the standards 11, said levers being secured together in slideable relation by means of pins 71. The lever 68 is provided with a projecting handle 72, said handle passing between a ratchet member 73 and one of the standards 11. The ratchet member 73 is provided with teeth 74, as shown in Fig. 6, so that the handle 72 can be secured in any position.

The method of operation of the form of my invention illustrated in Fig. 5 is as follows:

The felt sheets are secured at either side

on the hooks 35 and 36, the handle 72 being raised to its upper position for this purpose, thus lifting the lower stretching member 22 to its upper position. As soon as the felt sheets are secured on the rack, the handle 72 is pushed down and locked under one of the teeth 74 of the ratchet member 73. As the handle 72 is pushed down, the pin 71 is also pushed down, thus pushing down the end of the lever 69, and the lower stretching member 22 is also pushed downwardly through the member 64.

It will be noted that in the forms of my invention illustrated in Figs. 4 and 5, substitutes for the jack 28 are shown, these different methods being mechanically equivalent and providing ready means for stretching the felt sheets.

I claim as my invention:—

A felt sheet stretching and drying frame comprising a pair of standards, cross members pivoted on the bottom of said standards, a stationary stretching member secured at each end to each of said standards, a movable stretching member sliding freely on said standards, hooks on either side of said stationary and movable stretching member on which sheets of felt may be secured, a screw rigidly secured in one of said stretching members, a nut engaging the other member, and means by which an operator can turn said nut to force said members apart.

In testimony whereof, I have hereunto set my hand at Los Angeles, California, this 5th day of May, 1916.

JOHN R. BARRE.
